UNITED STATES PATENT OFFICE.

LOUIS C. WAGNER, OF NEW YORK, N. Y.

DESIGN FOR A CIGAR BAND OR WRAPPER.

No. 38,495.

Specification for Design.

Patented March 26, 1907.

Application filed February 27, 1907. Serial No. 359,694. Term of patent 7 years.

To all whom it may concern:

Be it known that I, LOUIS C. WAGNER, a citizen of the United States, residing at New York city, county of New York, and State of New York, have invented a new, original, and ornamental Design for a Cigar Band or Wrapper.

The design is illustrated in the accompanying drawing and shows a face elevation thereof.

I claim—

The ornamental design for a cigar band or wrapper as shown.

LOUIS C. WAGNER.
